TIRE MACHINE

Henry C. Bostwick, Coventry Township, Summit County, Ohio, assignor to The Akron Standard Mold Company, Akron, Ohio, a corporation of Ohio

Application December 27, 1933, Serial No. 704,120

11 Claims. (Cl. 154—10)

This invention relates to tire-building machines, and it has for its object to provide improvements in the mounting and operation of the band-stitching or rolling instrumentalities in such a machine, whereby the cost of construction and maintenance are reduced and efficiency increased.

Of the accompanying drawing, Fig. 1 is a front elevation of a tire-building machine provided with my improvements.

Fig. 2 is an end elevation, partly broken away.

Fig. 3 is a detail section on the line 3—3 of Fig. 1 through the radial-feed slide and its mounting.

Fig. 4 is a detail cross-section on the line 4—4 of Fig. 3.

Fig. 5 is an end elevation showing a modified hand-wheel shaft for the longitudinal stitcher feed.

In these views the cross-feed slide and parts carried thereby are shown in their band-rolling position.

In the drawing, 10 is a tire-building former in the shape of a flat-band building drum shouldered at its ends with reduced bead seats 11 for building a tire band with inextensible beads, the drum being of suitable segmental construction permitting it to be collapsed for removal of the completed band. The drum is carried by the outward end of a rotary driving shaft 12 projecting horizontally from a casing 13 containing the drum driving mechanism, said shaft being surrounded by a hollow shaft 14 for controlling the collapse and expansion of the drum.

The stitching or rolling devices, consisting of a pair of stitcher wheels 15 and their supports, are shown as mounted in this case rearwardly and below the level of the axis of rotation of the drum and provided with a rectilinear radial or cross-feed mounting for concurrently moving both stitcher wheels radially into and out of coaction with the drum or the material thereon, as well as a rectilinear longitudinal-feed mounting for moving the two wheels in opposite directions widthwise or axially of the drum.

A radial-feed slide 16 is mounted in a fixed guide 17 on the side of the casing 13 for rectilinear movement at an angle of substantially 30° to the floor line, the guide having a rear stop plate 17a for limiting the retracting movement of the slide. An anti-friction bearing is provided for said slide by interposing between the slide and the guide two endless traveling series of balls 18 operating in grooved races 19 on the slide and 19a on the guide, respectively at the upper and lower edges of the slide, the latter having return channels 20 for receiving the inactive portions of the respective ball groups.

Movement of the slide 16 in the direction of the drum shaft is imparted thereto at the will of

the operator by a pedal lever 21 pivoted upon a horizontal pin 22 carried by the end wall of the casing 13, said lever including a forwardly-projecting pedal arm 23 and another arm 24 connected by a link 25 with the slide. The link is pivotally connected by pins 26 and 27 respectively with the rear pedal-lever arm and the slide, and the pin 26 is adapted to occupy any one of a longitudinal series of holes 28 in the link, whereby the effective length of said link may be varied to accommodate the positions of the slide 16 to drums 10 of different diameters.

Mounted on the slide 16, to project horizontally therefrom, parallel with the axis of rotation of the drum, and to extend to and beyond the zone 15 of the drum, is an elongated flat bar 29 which acts as a guide for the stitcher slides and also as a support for their operating mechanism. Each stitcher wheel is freely journaled upon a spindle 30 carried by an arm of a lever 31 pivoted at 32 upon a supporting slide 33 which is mounted for movement along the bar 29. The other arm of said lever is backed by a helical spring 34 abutting a block 35 pivoted on the stitcher slide, for causing the stitcher wheel to engage the tire material upon the drum with a yielding pressure when the cross-feed slide is moved forward, these springs permitting the two stitcher wheels to yield independently to inequalities in the material and in rounding the shoulders of the drum. The spring 34 surrounds a rod 36 which has a stop nut 37 screwing on its lower end and coacting with the block 35 to limit the pivotal projecting movement of the stitcher lever on the slide 33.

For imparting the longitudinal feed to the stitcher slides 33 in opposite directions, there is provided a chain 38 mounted upon a pair of sprocket wheels 39 and 40 which are journaled upon the bar 29 at opposite ends of the latter, the upper stretch of the chain being secured by screws 41 to the left-hand stitcher slide 33 and its lower stretch secured by screws 42 to the right-hand stitcher slide 33. The inner sprocket wheel 40 is coaxially connected 45 with a shaft 43 projecting forwardly and upwardly to a position within convenient reach of the operator and there provided with a hand-wheel 44, for which might be substituted any other suitable means for turning the shaft. 50 The shaft 43 in this case is in two splined, telescopic sections 45 and 46, of which the lower or rear section 45 is carried by the sprocket wheel 40 and moves with the cross-feed slide 16, and the upper or front section 46 is mounted to turn 55 in a fixed bearing 48 on the end wall of the casing 13 and provided with suitable shoulders to hold it against axial movement in said bearing.

In the operation of this apparatus, the stitcher

wheels being together at the middle line of the drum at the beginning of the rolling operation, the cross-feed slide 16 is moved forward by means of the treadle lever 21 to bring said 5 stitchers against the tire material on the drum. While the radial pressure is maintained and the drum 10 is in rotation, the hand-wheel 44 is operated to move the stitcher wheels apart toward the drum shoulders, and when they have 10 completed their stroke, rolling down the tire material for the full width thereof, the foot pressure is relieved, the slide 16 and parts carried thereby are moved downwardly and rearwardly by gravity to retract the stitchers radially from 15 the drum, and the hand-wheel 44 is then turned in the reverse direction to move the stitchers toward each other to their initial positions.

The described mode of mounting the stitchers and their operating mechanism upon a cross- 20 feed slide having a rectilinear movement in an inclined path avoids the necessity of providing an outward support for the bar 29 or a base 25 mounting under the drum, dispenses with individual cross-feed mountings for the respective 30 stitchers and allows the operating shaft for imparting the longitudinal stitcher-feeding movement to be mounted directly in line with the feed devices carried by said slide and bar without the interposition of gearing or a universal 35 joint. The resulting simplicity increases the efficiency of operation and reduces the cost of manufacture and maintenance. The particular anti-friction bearing described for the cross-feed 40 slide provides the necessary rigidity for sustaining the radial pressure of the stitchers against the drum without cramping the movements of said slide.

In the modification illustrated in Fig. 4, a one-piece hand-wheel shaft 43^a without a sliding 45 joint is attached to the sprocket wheel 40 for operating the longitudinal feed, and its outer portion moves axially through the fixed bearing 48, so that the hand-wheel 44 participates in the movements of the cross-feed slide 16.

Various other modifications of embodiment 50 might be made within the scope of my invention as defined in the claims.

I claim:

1. Tire-building apparatus comprising a rotary 55 tire-building form, a stitching roller mounted rearwardly and below the axis of rotation of said form, a longitudinal stitcher guide parallel with said axis, a cross-feed slide carrying said 60 guide and mounted for upward, forward movement in an inclined path to bring the stitching roller into operative relation with the form, means carried by said stitcher guide for imparting longitudinal feed movement to the stitching roller, and a forwardly and upwardly extending operating member for the latter means.

2. Tire-building apparatus comprising a machine casing, a rotary tire-building form mounted on a shaft extending horizontally from said casing, an inclined guide on said casing, a cross- 65 feed slide mounted on said guide, a guide bar carried by said slide and extending horizontally parallel with the form shaft, below and rearwardly of the latter, a stitcher slidably on said 70 guide bar, and operator-controlled devices for actuating said slide and said stitcher.

3. Tire-building apparatus comprising a tire- 75 building form rotatable on a horizontal axis, a

stitcher movable radially into operative relation with said form, a slide carrying said stitcher and movable in an inclined, rectilinear path, cross-wise of said axis, from a rearward position below the axis, for so moving the stitcher, means carried by said slide for imparting feed movement to the stitcher longitudinally of said axis, and a lever for actuating said slide, having a forwardly-extending pedal arm.

4. Tire-building apparatus comprising a rotary tire-building form, a stitcher mounted for rectilinear movements radially and longitudinally of the axis of rotation of said form, the stitcher mounting including a cross-feed slide, and a 10 pedal lever for actuating said slide, having a 15 mechanical connection with the latter adjustable to accommodate forms of different diameters.

5. Apparatus according to claim 4 in which the connection between the lever and the slide is a 20 link pivoted to the two and having a longitudinal series of holes for one of the pivots to vary the effective length of the link.

6. Tire-building apparatus comprising a rotary tire-building form, a stitcher mounted for 25 movements radially and longitudinally of the axis of rotation of said form, the mounting including a cross-feed slide, a rectilinear guide therefor, an endless series of traveling anti-friction rollers interposed between said slide and guide, and a 30 longitudinal guide bar carried at one end by said slide and slidably supporting said stitcher.

7. Apparatus according to claim 6 in which the cross-feed guide is positioned at an inclined angle, rearwardly and below the form axis, and the anti-friction means consists of two endless 35 series of balls respectively at the upper and lower edges of the slide.

8. Tire-building apparatus comprising a rotary tire-building form, a guide bar located rearwardly and below the axis of rotation of said form and mounted for rectilinear cross-feed movement in an inclined path, a stitcher coacting with the form and mounted for rectilinear longitudinal sliding-feed movement along said bar, 40 a wheel carried by the bar for imparting said longitudinal movement, and a forwardly and upwardly-projecting manual-feed shaft coaxially connected with said wheel.

9. Tire-building apparatus comprising a machine casing, a rotary tire-building form thereon, a stitcher mounted for rectilinear cross-feed movement in an inclined path radially of the axis of rotation of said form and also mounted for sliding-feed movement longitudinally of said 55 axis, a control-shaft bearing on said casing, and a control shaft mounted to turn in said bearing on a fixed axis parallel with the cross-feed movement of the stitcher.

10. Apparatus according to claim 9 in which 60 the control shaft is in two telescopic, splined sections, the lower one of which partakes of the cross-feed movement of the stitcher and the upper one of which is held against axial movement in said bearing.

11. Apparatus according to claim 9 in which 65 the control shaft is axially slidable through as well as rotatable in said bearing and partakes as a whole of the cross-feed movement of the 70 stitcher.

HENRY C. BOSTWICK.
